UNITED STATES PATENT OFFICE.

JOHN F. BRENNAN AND CHARLES W. KREHER, OF NEW ORLEANS, LOUISIANA.

TAMPING MACHINE.

Application filed July 18, 1928. Serial No. 293,746.

This invention relates to tamping machines adapted to periodically elevate and release a tamping element therefor.

An object of the invention comprehends 5 a carriage for the mechanism by means of which the apparatus may be disposed directly over the work to be tamped.

An additional object of the invention contemplates a swinging mounting for the apparatus whereby the same may be shifted 10 from the sides of the carriage without necessitating a change in the position of the latter.

More specifically stated the apparatus is provided with a clutch mechanism by means 15 of which the operating device may be thrown into and out of engagement with the tamping element.

A cardinal object of the invention resides in the provision of holding elements for the 20 tamping element to sustain same in an elevated position while the carriage is being moved to another location.

With the above and other objects in view, the invention further consists in the following 25 novel features and details of construction, to be hereinafter more fully described, illustrated in the accompanying drawings and pointed out in the appended claims.

In the drawings:—

30 Figure 1 is a side elevation of the invention.

Figure 2 is a top plan view thereof.

Figure 3 is a front elevation of the invention.

35 Referring to the drawings in detail, wherein like characters of reference denote corresponding parts, the reference characters 10 and 11 indicate side channel bars adapted to be seated upon the upper sides of front and 40 rear axles 12 and 13 respectively. Wheels 14 are journaled upon the outermost ends of said axles.

45 Tie rods 15, having connection with spindle arms 16, carrying the wheels connected with the rear axle 13, are adapted for connection with the innermost ends thereof with an oscillating lever 17 pivotally mounted, as indicated at 18, upon the upper side of the axle 13 and having connection with a tongue 50 or other handle, such as indicated at 19. Such arrangement will permit turning of the wheels upon the axle 13, whereby the entire carriage may be steered in position for use.

55 A curved track 20, carried upon the forward ends of the bars 10 and 11, is disposed slightly in advance of the adjacent wheels

upon the axle 12, substantially as illustrated in Figure 2 of the drawings.

A supporting or base plate 21, having rollers 22 journaled between spaced parallel 60 disposed plate members 23 carried upon the underside thereof, are adapted to dispose their lowermost ends upon the opposite sides of the curved track 20 to prevent distortion 65 of said rollers and to provide a slide mounting for the base plate.

Channel bars 24, horizontally disposed upon the upper sides of the side rails 10 and 11, are adapted to support a block bearing or other spacing element, such as indicated 70 at 25, upon the upper sides thereof and which is centrally apertured to receive a bolt member 26 therethrough carried by the base plate 21 extended between the adjacent sides of the channel bars 24. A compression spring 27, 75 carried upon the lower end of the bolt member 26, behind the nut 26 therefor, is adapted to engage the underside of a plate member 29 carried upon the undersides of the horizontally disposed channel bars 24, whereby 80 the base plate 21 will be yieldingly retained in position for use.

A sleeve 30, vertically disposed upon the upper side and centrally of the base plate 21 in advance of the track 20, is adapted to accommodate a plunger rod 31 having a socket 32 within the lowermost end thereof. A tamping element, such as indicated at 33, having an upstanding trunnion 34 projected within a socket opening 32, is held against 90 displacement therein through the instrumentality of a set screw or other locking element 35.

Gusset plates 36, having connection with the opposite and outer sides of the sleeve 30, 95 are extended rearwardly thereof upon the upper side of the base plate 21.

An electric motor, gasoline motor or other source of power or prime mover, such as indicated at 37, upon the upper side of the base 100 plate 21, is provided with a driving gear 38 adapted for driving connection with a chain 39 trained over a driven gear 40 journaled between the gusset plates 36. A pinion gear 41, operable in conjunction with the driven 105 gear 40, is adapted for meshing engagement with a relatively large gear 42 loosely mounted upon a shaft member 43 and journaled between the respective gusset plates 36. The gear 43 carries a drum or cam face 44 110 upon its outer side operable by a clutch lever 46 carried upon the shaft 43.

Spaced driving sprockets 47, fixed upon the shaft 43 adjacent the inner side of the plunger rod 31, are adapted for connection with pairs of chains 48 which also travel over 5 idler and adjusting sprockets 49 and 50 respectively.

Lifting elements, in the nature of plates 51, horizontally disposed and forming the means of connection between the respective chains 48 10 and disposed at intervals thereon, are adapted for selective engagement with studs 52 arranged adjacent the uppermost end and inner side of the plunger shaft 31. When the source of power 37 is set in motion and the 15 clutch mechanism shifted to occupy the position shown in Figure 3 of the drawings, the chains 48 will travel to periodically elevate and release the plunger shaft 31, whereby the tamping element 33, when liberated from its 20 lifting influence, will drop with a gradually gathering velocity due to its weight until same is stopped, due to contact with the material being tamped.

A ratchet gear 53, carried by the shaft 43, 25 is adapted for engagement with a pawl or dog 54, carried by the sleeve 30, whereby the plunger shaft 31 may be held in the position shown in Figure 1 of the drawings, while the carriage is being moved about from place to 30 place.

A handle member 55, carried upon the forward end of the base plate 21, may be employed for laterally shifting the same from its pivot point to move across the track 20 35 therefor, whereby the tamping element 33 may be disposed in position for use across a road bed or a ditch being filled.

The adjusting sprockets 50 may be employed to take up slack in the chains 48 and 40 which in like manner to the idler sprockets 49 are arranged between plate members 56 raised adjacent the uppermost ends and opposite sides of the sleeve 30.

Although I have described the present invention as being primarily adapted for use in the tamping of ditch fillings, road ballasts and the like, it is obviously understood that I do not limit myself to the embodiment of the invention described but that the same may 45 be equally and effectually as well applied for other uses.

The invention is susceptible of various changes in its form, proportions and minor details of construction, and the right is here- 50 55 in reserved to make such changes as properly fall within the scope of the appended claims.

Having thus described the invention, what is claimed is:—

1. A tamping machine comprising a carriage having a track upon one end thereof, a supporting plate pivotally mounted at one end upon the carriage and slidably mounted at its opposite end upon the track, a lifting apparatus supported upon the plate, a plunger shaft slidably mounted adjacent the sliding end of the plate, studs carried by the shaft, and means operable by the lifting apparatus to periodically engage, elevate and release said studs. 60 65

2. A tamping machine comprising a carriage having a curved track upon one end, a supporting plate pivoted at one end upon the track and slidably mounted at its other end upon said track, a sleeve vertically disposed upon the slidably mounted end of the plate, 70 a plunger shaft carried therein, a lifting apparatus carried upon the base plate, chain members operable by the lifting apparatus, studs horizontally disposed upon one side and adjacent the uppermost end of the plunger 75 shaft, plate members having connection at their ends with said chains and arranged at spaced intervals in the lengths thereof for selective engagement with said studs to periodically elevate and release said studs, and a tamping element carried upon the lowermost 80 85 end of the plunger shaft. 90

3. A tamping machine comprising a carriage having a curved track upon one end, a supporting plate pivoted at one end upon the track and slidably mounted at its other end upon said track, a sleeve vertically disposed upon the slidably mounted end of the plate, a plunger shaft carried therein, a lifting apparatus carried upon the base plate, chain members operable by the lifting apparatus, 95 studs horizontally disposed upon one side and adjacent the uppermost end of the plunger shaft, plate members having connection at their ends with said chains and arranged at spaced intervals in the lengths thereof for selective engagement with said studs to periodically elevate and release said studs, a tamping element carried upon the lowermost end of the plunger shaft, and means for sustaining the plunger and tamping members therefor in an elevated position while the carriage 100 105 is in transit. 110

In testimony whereof we affix our signatures.

JOHN F. BRENNAN.
CHARLES W. KREHER.
